Inventor
Charles B. Hibbard.

UNITED STATES PATENT OFFICE.

CHARLES B. HIBBARD, OF GRAND RAPIDS, MICHIGAN.

SPOON-BAIT.

SPECIFICATION forming part of Letters Patent No. 295,758, dated March 25, 1884.

Application filed June 28, 1883. (Model.)

To all whom it may concern:

Be it known that I, CHARLES B. HIBBARD, of Grand Rapids, in the county of Kent and State of Michigan, have invented certain new and useful Improvements in Spoon-Baits; and I do hereby declare the following to be a full, clear, and exact description of the invention, such as will enable others skilled in the art to which it pertains to make and use it, reference being had to the accompanying drawings, which form part of this specification.

My invention relates to improvements in spoon-baits, of the class wherein the spoon is attached to a supporting-wire by a yielding connection which permits the spoon to be moved inwardly, and when the pressure is released to return to its ordinary position.

The object of my invention is to simplify the construction of the connecting devices, and also to locate them so that they will not interfere with the action of the spoon or with the line.

My invention consists in the peculiar construction and arrangement of the parts composing the device, as will be fully hereinafter explained.

In the accompanying drawings, Figure 1 is a side elevation. Fig. 2 is a detail of lever F. Fig. 3 is an elevation of the spoon. Fig. 4 is an end view.

In the accompanying drawings, A represents the wire having a loop at each end, to which are attached the hook and line.

C represents the spoon, having at its forward end an eye which slides upon the rod, and is limited in its motion by the inner end of the loop. Upon the spoon C is soldered a spring, D, composed of a length of wire bent to form a double spring and having its bent portion formed in a loop. Between the parallel sides of the spring is soldered a stop, E, the free end of which is curved outwardly and then down, as shown. The spring is connected

to the wire by an arm or lever, F, having at one end an eye, b, which slides upon the rod, and at the other end a curved loop, c, which is clearly illustrated in detail in Fig. 2. The straight portion of the lever passes between the parallel sides of the spring, and is then curved round and under such spring, as shown, the lower portion of the loop fitting within the space left by forming the curve in the end of the stop, as before described. Obviously now the spoon may revolve on the wire and may slide freely back and forth thereon. At the same time the spoon may be pressed inwardly, which will cause the loop on the end of the lever to work under the spring and slightly raise the same, the stop limiting such motion at the proper point. When the pressure is released, the return of the spring D forces the loop outward from the same, and thereby changes the relative position of the spoon and its supporting-wire, until such parts assume their first positions.

I am aware that spring-connections between the spoon and its supporting-wires are not new, and I do not make any claim, broadly, to such construction, my claims being limited to the improvement in details which I have invented.

What I claim is—

1. The combination of the wire A, the spoon C; the spring D, secured to the spoon, and the independent lever F, connected to the spring at one end, as described, and at the other to the wire A.

2. The combination, with the wire A and sliding lever F, of the sliding revolving spoon C, having the doubled spring-rod D and stop E, substantially as described.

CHARLES B. HIBBARD.
